TOOTH BRUSH

Howard C. Peterson, Arlington, S. Dak.

Application May 17, 1937, Serial No. 143,230

1 Claim. (Cl. 15—167)

This invention relates to new and useful improvements in toothbrushes which are especially adapted for use in brushing the teeth and massaging the gums.

The primary object of the invention is to provide a toothbrush having a bristle arrangement which is most practicably adapted to all interproximal spaces of either dental arch of average size, thereby eliminating unnecessary bending of the bristles, which will enable the bristles to function in an orderly fashion to lessen gum injury and which will materially increase the life of the brush; which will enable the bristles to reach the hidden areas most susceptible to decay; and which will effect reinforcement of the particular bristles intended to reach the most inaccessible areas, thereby making the brush more adapted to the sweeping motion used in gum massage.

Other objects and advantages of the invention will be apparent during the course of the following description.

In the accompanying drawing forming a part of this specification and in which like numerals are employed to designate like parts throughout the same:

Figure 1 is a side elevational view of a complete toothbrush embodying this invention;

Figure 2 is an end elevational view of the toothbrush head detached from the handle;

Figure 3 is a plan view of the handle portion of the toothbrush illustrated in Figure 1 with the head disclosed in Figure 2 detached therefrom;

Figure 4 is a partial plan view of the upper dental arch illustrating the spacing of the rows of bristle groups lengthwise of the brush head to most practically adapt the brush to the interproximal spaces of the dental arch;

Figure 5 is a similar view to Figure 4 and illustrates the adaptability of the bristles for brushing the lingual surfaces of the teeth when the brush is moved lengthwise;

Figure 6 is a schematic view disclosing portions of the upper and lower jaws and illustrating the adaptability of the bristles for massaging the gum tissues and brushing the interproximal areas most susceptible to decay; and

Figure 7 is a schematic view disclosing a portion of an upper jaw and illustrates the adaptability of the bristles to the occlusal or morsal surfaces and to the gingival cavities.

Referring particularly to Figures 1 to 3 inclusive, there is shown a toothbrush head which includes the back 10 which has projecting from

one face thereof a plurality of transversely extending rows of bristle groups, the rows being designated as such by the reference character 11. This row formation is best illustrated in Figure 1. By inspecting Figure 2, it will be seen that each row 11 is made up of three groups of bristles which are designated by the reference character 12 for the center group and 13 for each side group.

Referring to Figure 1, it will be seen that the various transverse rows 11 of bristle groups are spaced longitudinally of the brush head 10 a greater distance than is conventional with toothbrush arrangements. These rows of bristles are spaced approximately five millimeters from center to center. This spacing is most practicably adapted to all interproximal spaces of either dental arch of average size. It will be noted that the bristles forming each row 11 are of proper length to provide wedge-shaped or tapered outer end portions. These tapered extremities permit the bristle rows to penetrate, to a considerable extent, the spaces between the teeth, as is clearly illustrated in Figure 4. Each of the three groups of bristles 12 and 13, when viewed at an end of a row as in Figure 1, is formed with the same diameter at its base or where it leaves the backing member 10.

Referring particularly to Figure 2, it will be noted that the center group of bristles 12 is approximately twice the diameter of the side groups of bristles 13 at the bases of said groups. The diameter of the center group 12 is approximately five millimeters. The diameter of each side group 13 is approximately two and one half millimeters. The groups 12 and 13 are spaced preferably approximately one millimeter at their bases.

Figure 2 discloses the fact that the contour formed by the extremities of the bristles in a row forms an arc of marked degree. The longest bristles of the center group 12 preferably measure approximately fifteen millimeters in length. The shortest outside bristles for the side groups 12 measure approximately nine millimeters in length. This close positioning of the shorter groups 13 relative to the comparatively long and wide group 12 enables the side groups to reinforce the center group and accomplishes uniform application of the bristles to the gum tissues when the buccal, the labial, and the lingual areas of the gums are being massaged, as illustrated in the positions a and b of Figure 6.

For the sake of economy, I have disclosed the brush head 10 as being detachably connected to

- the handle 15. This handle includes a pair of resilient fingers 16 which are provided at their extremities with inwardly directed knobs 17. Figure 2 discloses the brush back 10 as having 5 grooves 18 extending longitudinally of its side edges with depressions 19 formed at the inner ends of the grooves. The grooves 18 receive the fingers 16 while the knobs 17 carried by the fingers are received within the depressions 19.
- 10 Positions *c* and *d* of Figure 6 and position *e* of Figure 4 illustrate the adaptability of the arrangement of the rows 11 and the contour of these rows for brushing the interproximal spaces between the teeth. Positions *c* and *d* illustrate 15 the manner in which the tapered extremities 14 (see Figure 1) are capable of reaching the areas most susceptible to decay and indicated by the reference characters *f* and *g* in Figure 6. Figure 5 illustrates the position *h* of the brush and discloses the adaptability of the bristles to treat 20 the lingual surfaces of the teeth when the brush is manipulated lengthwise.
- Position *i* of Figure 7 illustrates the adaptability of the bristles to the occlusal or morsal surfaces of the teeth, thus approaching the areas 25 where the pit and fissure class of cavities begins, as designated by the character *j* in this figure. The position designated by the character *k* in Figure 7 discloses the adaptability of the bristles 30 to the gingival portion of a tooth wherein cavities of the character designated by the reference character *m* form and which are classified as the gingival third cavities.
- It is believed to be unnecessary to describe in 35 detail the manner in which the toothbrush structure embodying this invention is employed for

brushing the teeth and massaging the gums. Figures 4 to 7, inclusive, very clearly illustrate these uses of the brush.

It is to be understood that the form of this invention herewith shown and described is to be taken as a preferred example of the same and that various changes in the shape, size, and arrangement of parts may be resorted to without departing from the spirit of the invention or the scope of the subjoined claim.

Having thus described the invention, I claim:

A toothbrush of the type described comprising a back member having projecting from one face thereof a plurality of transversely extending rows of bristle groups with three closely positioned 15 groups to each row, all of the said rows being spaced a distance substantially equal to that of the inter-proximal spaces of either dental arch of average size, the bristles forming each row being of proper length transversely of the row to 20 collectively form a tapered outer end portion and longitudinally of the row to collectively form an arc with the bristles at the center of the arc being of greater length than the bristles at the opposite sides of the row and with this difference in 25 length exceeding the spacing between said rows, all of the groups of bristles forming each row being of equal diameter transversely at the base of the row, the center group of bristles of each row having a diameter at its base and longitudinally 30 of its row which approximately equals the spacing between rows, the end groups of each row having a combined diameter at their base and longitudinally of the row which approximately equals the said diameter of the center group.

HOWARD C. PETERSON.
